ATTORNEY

UNITED STATES PATENT OFFICE

HARRY G. JOHANSEN, OF ST. LOUIS, MISSOURI

DESIGN FOR A SHOE

Application filed June 10, 1932. Serial No. 44,047. Term of patent 3½ years.

To all whom it may concern:

Be it known that I, HARRY G. JOHANSEN, a citizen of the United States, residing at St. Louis, Missouri, have invented a new, original, and ornamental Design for Shoes, of which the following is a specification, reference being had to the accompanying drawing, forming part thereof.

Figure 1 is an elevation of one side of the shoe.

Figure 2 is an elevation of the other side of the shoe.

Figure 3 is a top view of the shoe.

The novel design is formed by contrasting materials, the edges of which produce a se-

ries of curving lines extending generally longitudinally of the shoe and creating an appearance of speed and grace corresponding to a streamlining effect. The dominant feature of the design is the provision of a series of elements abreast of the ball and arch portions of the shoe extending longitudinally of the foot and forming a conventionalized Mercury wing effect.

I claim:

The ornamental design for a shoe substantially as shown and described.

HARRY G. JOHANSEN.
